UNITED STATES PATENT OFFICE.

KARL KLEINERT, OF STUTTGART, GERMANY, ASSIGNOR TO ROBERT BOSCH AKTIEN-
GESELLSCHAFT, OF STUTTGART, GERMANY.

SEARCHLIGHT.

Application filed February 17, 1926, Serial No. 88,873, and in Germany March 16, 1925.

This invention relates to a mounting for a dirigible searchlight, especially adapted for use on power vehicles, in which the searchlight is mounted for movement in two planes, and which is adapted to be operated by the driver without leaving his seat even when the vehicle is enclosed.

Prior art proposals along this line are objectionable because two separate manipulations of the operating handle are necessary in case it is desired to adjust the searchlight in two planes, because there is no natural connection or relation between movement of the handle and the searchlight when the handle is moved to adjust the searchlight, because the adjustment is limited and is made with difficulty, or because the mounting and operating mechanism are complicated.

The present invention has for its object the provision of a simple adjustable searchlight mounting in which the above objections are eliminated.

In the accompanying drawing, in which two forms of constructions of the subject matter of the present invention are illustrated, Fig. 1 shows a searchlight with rack-bar drive in longitudinal section: Fig. 2 is a cross section on the line A—B of Figure 1, Fig. 3 shows a searchlight with double gear drive partly in side view and partly in longitudinal section, while Fig. 4 is a side view of Fig. 3.

In the construction illustrated in Figs. 1 and 2, a hollow shaft *a* projects through a wall 1 of the vehicle and is rotatably mounted in the flanges or supporting guides *b*, *b*. On the ends of the shaft *a* casings *c*, *c* are secured by means of the stud bolts *d*, *d* respectively. In the longitudinal bore *e* of each of said casings a rack-bar *g* is arranged in such manner that it can slide in a horizontal or longitudinal direction. Said rack-bar *g* meshes at its ends with pinions *h*, *h* which are arranged in the bores *f*, *f* of the casings *c*, *c* and are secured by keys *k*, *k* on the bolts *i*, *i*. The casing *c* which is provided on the side operating the searchlight is enclosed by the two arms, *n*, *n* of a lever *l* in such a manner that the bolt *i* projects through the two arms *n*, *n* and can be secured to the lever *l* by means of a pin *m*. In the same manner the second bolt *i* on the searchlight side of the wall 1 is secured by means of a pin to the searchlight

carrier *o*, the two arms of which enclose the casing *c*.

In the construction shown in Figs. 3 and 4, bevel gear wheels *q* and *s* are substituted for the spur gear wheels *h*, *h*, which bevel gear wheels mesh with the bevel gear wheels *r* and *t*, respectively, secured on a shaft *v* which latter is arranged within the hollow shaft *a*. The two bevel wheel pairs *q*, *r* and *s*, *t* have the same ratio of transmission.

The hand lever *l* and the search light carrier *o* are suitably secured to bolts *i*, *i* in such a manner that the axes of the hand lever *l* and of the searchlight *p* are parallel.

The operation of the two described forms of construction is as follows: In Figure 1 the searchlight is turned by the oscillation of the hand lever *l* around the axis *i* whereby the pinion *h* longitudinally displaces the rack-bar *c* so that the other pinion *h* and the searchlight support which is rigidly secured to said pinion, are turned through the same angle and in the same direction as the lever *l*. In the modification illustrated in Figure 3 the movement of the lever *l* is transmitted by means of the bevel wheel pairs, *q*, *r* and *t*, *s* for the same amount and in the same direction to the searchlight support *w*, which is rigidly secured to the bevel wheel *s*, as the bevel wheels *q* and *s* are arranged on opposite ends of the axis of the shaft *b*. In both forms, the axes of the searchlight and operating handle gears are parallel and the operating handle and the rays of light from the searchlight extend in parallel lines.

While in the structure shown in Figs. 1 and 2, the searchlight cannot perform a complete rotation in the plane vertical to the image or object to be focused, the searchlight in the construction shown in Figs. 3 and 4 is so spaced laterally from the hollow shaft *a* by a sufficient extension of the shaft *w* that the said searchlight can describe a complete circle around the shaft *w* without interference from the hollow shaft *a*.

Vertically to the image plane the searchlight is oscillated by turning the hollow shaft *a* by means of the hand lever *l*.

It will be seen, therefore, that the present invention permits the adjustment of the searchlight in any desired direction by a single manipulation of the lever, without it being necessary to turn the light first in one

plane and then in the other plane. As the turning angle of the searchlight and of the hand lever can be made equal both as to amplitude and also direction, and as the rotation of the searchlight and of the hand lever are in the same direction, the adjustment of the hand lever on the object to be illuminated results simultaneously in the desired adjustment of the searchlight. By reason of the fact that the operating handle and the searchlight extend in the same direction, the adjustment can be made quickly and naturally. Furthermore the turning angles are unlimited and the required driving power remains all ways equal.

I claim:

1. Mechanism operable through a wall for operating a searchlight in two planes comprising a supporting guide, a hollow shaft 20 rotatably supported therein, gear wheels mounted on parallel axes extending transversely of said shaft, means transmitting rotation of one of said gear wheels to the other, a searchlight connected to one of said gear 25 wheels and one end of said shaft, and an operating lever connected to the other end of the shaft and the other gear wheel, movement of the lever causing the search light to follow

the same angular movement and to take up the same relative position as said lever in any movement of the lever.

2. Mechanism for operating a searchlight in two planes comprising a supporting guide, a hollow shaft rotatably supported therein, 30 housings secured to the ends of said hollow shaft, a second shaft arranged within said hollow shaft, parallel shafts extending transversely of said second shaft and rotatably mounted, one in each housing, gearing connecting said second shaft to said parallel 35 shafts, a handle connected to one of said parallel shafts, and a searchlight connected to the other parallel shaft, movement of the lever causing the searchlight to follow the same 40 angular movement and to take up the same 45 relative position as the lever in any movement thereof.

3. Mechanism as set out in claim 2 in which the searchlight is displaced laterally on its supporting shaft with respect to the hollow 50 shaft to such an extent that the searchlight can describe a complete revolution about said hollow shaft.

In testimony whereof I have hereunto affixed my signature.

KARL KLEINERT.
